US0D1049753S

(12) **United States Design Patent** (10) Patent No.: **US D1,049,753 S**
(45) Date of Patent: ** Nov. 5, 2024

(54) **BOILING POT**

(71) Applicant: **Shenzhen Crazymonkey Technology Co., Ltd.**, Shenzhen (CN)

(72) Inventor: **Haibao Wu**, Shenzhen (CN)

(73) Assignee: **Shenzhen Crazymonkey Technology Co., Ltd.**, Shenzhen (CN)

(**) Term: **15 Years**

(21) Appl. No.: **29/951,669**

(22) Filed: **Jul. 10, 2024**

(51) LOC (14) Cl. **07-02**

(52) U.S. Cl.

USPC **D7/360**; D7/361; D7/359
